(57) **CLAIM**

We claim the ornamental design for a shelving unit, as shown and described.

DESCRIPTION

FIG. 1 is a front perspective view of a shelving unit of a first embodiment showing our new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front perspective view of a shelving unit of a second embodiment showing our new design;

FIG. 8 is a front elevational view thereof;

FIG. 9 is a right side elevational view thereof;

FIG. 10 is a left side elevational view thereof;

FIG. 11 is a top plan view thereof; and,

FIG. 12 is a bottom plan view thereof.

The broken lines depict unclaimed environmental subject matter and form no part of the claimed design.
